UNITED STATES PATENT OFFICE.

CHARLES LEWIS ROBERTS, OF LOUISVILLE, KENTUCKY, ASSIGNOR TO THE AMERICAN TOBACCO COMPANY, OF NEW YORK, N. Y., A CORPORATION OF NEW JERSEY.

METHOD AND APPARATUS FOR STEMMING TOBACCO.

Application filed June 11, 1925. Serial No. 36,297.

This invention is an improvement in methods and apparatus for stemming tobacco and more particularly in methods and apparatus designed to conserve as large a proportion of the leaf unbroken as possible.

One of the problems most difficult of solution in stemming tobacco, is to thoroughly remove all of the large woody portion of the stem, not suitable for utilization with the lamina, while leaving the portions of smaller size, which are entirely suitable for such use, and without too great disintegration of the leaf.

In methods at present practiced, the lamina is stripped from the main stem while it is grasped in some portion of its length, to provide counter-resistance, or the leaf is subjected to the action of disintegrators which break it up, the lighter leaf portions being afterwards screened, or otherwise separated from the heavier stem portions.

The results attained by the former method are unsatisfactory, in that a relatively large proportion of the valuable lamina remains with the woody stem portion, and the separated lamina contains too great a proportion of the undesirable stem. The method moreover is slow and expensive requiring as it does, individual treatment of the leaves.

In both methods, the leaf is greatly mutilated and torn and in the latter method especially a relatively large amount of the leaf is converted into particles too small to be handled easily in all of the further processes to which the tobacco is subjected. As for instance such particles are not easily flavored, and hence not suitable for processes in which flavoring is required.

A relatively large proportion of the central stem, from one third to one half at the tip end of the leaf, is entirely suitable for all purposes, for which the leaf is to be used, and it is not necessary, or even desirable, that this portion of the leaf be subjected to the action of stemming mechanism, with the consequent liability to mutilation of the lamina.

One of the principal objects of the present invention is the provision of a method whereby a relatively large proportion of the lamina with stem portions of a size which does not unfit them for use with the lamina, is removed prior to the initiation of the operation for removing the stem, thereby

to retain such portion in its original unbroken condition.

Another object is the provision of an apparatus for carrying out the method, including means for effectually removing the undesired stem portions, and mechanisms for separating and removing from the leaves in an unbroken condition the tip portions which contain utilizable stem.

Another object is the provision of means and mechanism of the character specified, adapted to operate upon the leaf in the hand, and with a minimum of manual manipulation.

With these and other objects in view the invention consists in the method and the several steps thereof, and in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings:

Fig. 1 is a side elevation of the apparatus, with parts in section, and shown somewhat diagrammatically.

Fig. 2 is a plan view.

Fig. 3 is a vertical longitudinal section of one of the disintegrators of the first series.

Figs. 4 and 5 are similar views of other machines of the first series.

Figs. 6 and 11 are sections on the lines 6—6, and 11—11, of Fig. 2.

Fig. 7 is a longitudinal vertical section through the dust screening device.

Fig. 8 is a longitudinal vertical section of the last disintegrator.

Fig. 9 is a section on the line 9—9 of Fig. 8.

Fig. 10 is a longitudinal vertical section of the fiber fan.

In the present embodiment of the invention, the apparatus for carrying out the improved method is arranged on three floors, indicated at A, B, and C respectively, in Fig. 1, although it will be understood that this arrangement is a matter of convenience. The stemming apparatus in the present instance is upon the intermediate floor B, the receptacles for the leaf, stems and dust on

the lower floor A, while the blending and tip separating mechanism is arranged on the third floor C.

The blending mechanism comprises an endless belt or conveyor 1, which is supported at its ends by rollers 2, one of which is driven by means of the pulley 3 and a belt 4, from a suitable prime mover not shown. The rollers 2 are journaled in suitable supports 5 on the floor, and the upper run of the belt moves through a channel shaped guide 6, which extends the full length thereof as shown, retains the tobacco on the belt during its travel toward the tip separating mechanism to be described.

The tobacco indicated at 7 is arranged upon the floor C, with the various grades in separate piles, arranged in lines on opposite sides of the belt, the piles being usually 20 cylindrical, just as the tobacco comes from the hogshead. The tobacco is blended on the belt by one or more operators, each placing on the belt the proper proportion of tobacco from each grade to produce the blend desired. The tobacco is in the hand as shown, and it may be placed upon the belt in bunches of hands if desired.

At the delivery end of the belt, mechanism is arranged for dividing the leaves into two 30 portions, one of which contains all of the large woody stem portion which it is desired to remove, while the other contains only finer stem portions, which are utilizable in the usual processes to which the tobacco is subjected.

The said mechanism which is fully shown and described in my co-pending application Ser. No. 36,298 of even date herewith, includes a table 8 supported above the floor, 40 and a plurality of endless belts 9 so arranged that the upper runs of the belts travel upon the table top, side by side, but spaced apart from each other. The upper runs of the belts travel in the same direction, and at the 45 end remote from the blending mechanism, the belts deliver through openings in the table, into chutes 10 and 11, for the stem and tip portions respectively.

A pair of holding chains for the tobacco 50 cooperates with each of the belts 9. The chains of both pairs are supported by shafts 12 journaled transversely of the table, one of which is driven in any suitable manner, and the chains are of a length such that there will be a relatively large amount of slack in the lower run of each, the lower runs cooperating with the belts 9.

The upper runs of the chains are supported by a guide or guides 13, and a pair 60 of cooperating disk cutters 14, are arranged between the pairs, and between the shafts 12 for dividing the leaves into two portions, as they are carried past the cutters by the belts and chains. The cutters lap, 65 and the common chord of thelapping seg-

ments is at about the level of the upper faces of the belts. The cutters are driven from the prime mover, by a belt 14', and they are geared together as indicated at 15.

An operator standing at the point X 70 places the hands as they are delivered from the upper run of the belt 1, on the upper runs of the belts 9, and it will be noticed that the belts 9 are extended beyond the chains at the inlet end of the cutting mechanism. As the hands still unbound are carried past the cutters, the leaves are separated into two portions. The hands are arranged with the butts toward the operator, and with the tips of the hands in approximate alinement, so that the cut off tips of the leaves are of approximately the same length. The butt ends are delivered into the chute 10, while the tip ends are delivered into the chute 11.

The tip ends are suitable for further processing, such for instance as flavoring, in the manner set forth in my co-pending application Ser. No. 36,299 of even date herewith, while the butts are subjected to a disintegrating action, to break up the stem portions, and remove the lamina from the stem portions. The lamina recovered in the process of disintegration is utilized in the manner set forth in the said last named application, the larger portions being flavored in the usual manner, while the smaller portions in the dry state are agglomerated with the tip or larger portions.

Preferably a plurality of individual disintegrators, which may be of the cylinder and concave type, are arranged in series, or cascade, each delivering to the succeeding. The butt portions of the hands above mentioned, are fed into the first disintegrator, 100 and the last usually delivers to a preceding.

The type of disintegrator, the relative arrangement of the several pieces of the apparatus, as also the layout of the plan, is a 110 matter of convenience, and while that to be described is a convenient arrangement, including disintegrators of an accepted type, it is illustrative only. In the present arrangement, the operation is cyclic, each disintegrator including mechanism for removing from the cycle, leaf particles above a selected weight, and in the cycle, preferably at the last disintegrator, there is a gravity discharge, for the stem portions.

In the present instance, the disintegrators are five in number, indicated at D, E, F, G, and H, respectively, although it will be understood that the number will be more or less, as may be found advisable. All of the disintegrators are of the cylinder and concave type, but preferably the relative density of the spacing of the teeth of the cylinder and concave increases from the first disintegrator to the last. Except for this spac-

ing, the disintegrators D, E, F and G are alike, and but one will be described.

Each is composed of a suitable casing 20 having a hopper extension 21 into which the tobacco to be disintegrated is delivered, it being understood that the chute 10 delivers directly into the hopper extension of the disintegrator D. The bottom of the hopper is formed into a concave 22 having teeth 23, which cooperate with similar teeth 24, on a cylinder 25, journaled co-axially with the concave. Each cylinder has in connection therewith fast and loose pulleys 26, for connection with a suitable prime mover, and other pulleys 27 and 28 on the opposite side of the casing from the pulleys 26. Belts 29 and 30 connect the pulleys 27 and 28 with pulleys 31 and 32 respectively, the former on the shaft 33 of a roller 34, and the latter on the shaft 35 of a fan or blower 36. The fan 36 is mounted in the upper part of the casing, and the roller 34 is one of a pair, the other indicated at 37.

The axes of the rollers are in the same plane, and each is journaled in an extension of the casing, the extensions indicated at 38 and 39. A screen 40 in the form of an endless belt is supported by the rollers, and the runs of the belt extend transversely of the casing, between the fan and the cylinder. Pairs of horizontal guides 41 are provided for the respective runs, and the belt forms a moving screen. The leaf particles above a selected weight are driven by the blast of the fan against the screen, which strains the particles from the blast, and delivers them at the rear of the casing, the casing having a delivery opening just below the roller 34, it being understood, that the lower run of the belt moves rearwardly.

The leaf particles are swept from the belt as it passes up around the roller 34 by a rotary brush 42, driven by contact with the belt. A spring pressed roller 43 cooperates with the roller 34, and the lower run of the screen belt passes between the rollers 34 and 43.

All of the leaf particles above a selected weight are delivered by the rollers 34-43, onto a conveyor to be described, while those below this weight pass over a deflecting board 48, onto an endless conveyor 49, which delivers such particles to a succeeding disintegrator. The belt is supported by a roller 50, journaled below the deflecting board 48, and a roller 51 journaled on the hopper of the succeeding disintegrator. The upper run of the belt 49 moves over a guide or grain board 52, which extends between the rollers 50 and 51, and cooperates with the grain board 48, to provide a hopper shaped bottom, for the disintegrator. Guard plates 53 are placed at opposite sides of the grain board 52 to prevent displacement of the leaves.

The leaf particles delivered between the rollers 34 and 43 fall upon an endless belt or apron 54, supported by rollers 55 journaled in suitable supports 56. The belts 54 move at right angles to the belts 49, and deliver onto a common belt 57, extending parallel with the belts 49, and supported in a manner to be presently described. The rollers 55 remote from the disintegrators are driven by the belts 59 from a suitable prime mover.

Each of the fans 36 is journaled in a suitable fan casing 60 in the upper part of the casing 20. Each casing 60 has an axial inlet, which may be regulated as to capacity by a damper 62, and the tangential outlet of each fan communicates by a conduit with a dust collector, the disintegrator D by means of a conduit 66 with a collector 67, and the disintegrators E, F and G with a collector 68, by means of similar conduits 69. In these collectors 67 and 68, the particles of tobacco settle, and are delivered through chutes 71 and 72 to a sand screen and riddle device, to be described, while the dust passes off through flues 70.

The violence of the blast, passing upward through each screen 40 is regulated by means of gates or louvers 73 in an inclined partition 74 below the screen. The picking belt 57 is supported by rollers 75 journaled in suitable supports 76, one roller being adjacent to the first disintegrator, and the other near the last of the first series, that is the disintegrator G. This belt moves toward the left of Fig. 2, and delivers the leaf particles to other mechanism to be described.

The last disintegrator in the present instance is of the Cardwell type, having a plurality of assemblages of cylinder and concave, and a riddling device in connection with the screening mechanism. The disintegrator includes a suitable casing 77 into one end of which the conveyor 49 of the thrasher or disintegrator G delivers. The delivered tobacco passes down over a deflecting board 78, to the first cylinder-concave assemblage, composed of the cylinder 79 and the concave 80. The second assemblage comprises a cylinder 81 and a concave 82, arranged in series with the first assemblage. The concaves are arranged below and in front of the cylinders, and cover less than 90 degrees of the surface thereof. A perforate plate or screen 85 is arranged between the concaves 80-82, over which the tobacco passes from the first assemblage to the second, and those particles which are small enough pass through the openings of the plate.

The cylinders are journaled in the walls of the casing, and each is provided with a pulley 86 and 87 respectively, connected by a belt 88. The cylinder 79 is driven by a belt 90 which connects a pulley 89 on the

cylinder 79, with a pulley on a cam shaft 94 to be described.

The riddling device includes a box frame 91, which is supported in inclined position, 5 and for swinging movement longitudinally of the casing 77, by means of links 92. The links are resilient, rigidly connected at one end to the casing 77, and at the other pivoted to the frame and allow a to and fro movement of the frame.

The frame is vibrated or reciprocated by means of a cam 95 on a shaft 94. The shaft is driven by a belt, connecting a pulley 97 on the shaft, with a prime mover. A link 96 13 connects the box frame with a follower 95' on the cam. Three perforate screens 99, 100, and 101 are arranged transversely of the box frame in substantial parallelism. The mesh of the screens decreases from the upper to the lower, and the tobacco from the cylinder and concave assemblages delivers onto the upper screen 99. A bridge 102 is arranged transversely of the screen, at the delivery point of the assemblage 81—82. The tobacco from the assemblage 81—82 delivers onto the bridge, and over the lower edge thereof, while that from the assemblage 79—80 delivers beneath the bridge.

The disintegrated tobacco leaves move rearwardly over the screen 99, and overflow the lower end into a trough 104. Those particles which pass through the meshes of screen 99, gradually travel to the rear end of the screen 100, and discharge through an opening 105 into the trough 104. The trough 104 moves with the box frame, and the jarring movement imparted to the leaves, tends to separate the lighter from the heavier portions by gravity. The heavier portions seek the bottom of the trough, while the lighter overflow the rear wall thereof into an air blast, which removes those particles of a selected buoyancy from the cycle. Those particles of stem devoid of lamina are discharged by gravity, the disintegrator having a gravity discharge for this purpose.

A fan or blower assemblage indicated generally at 106 provides the air blast, and the tangential outlet of the fan indicated at 107 inclines upwardly and rearwardly. The front wall of the outlet has an opening through which the trough 104 delivers, and the rear wall a gravity discharge 109. The discharge 109 delivers into the hopper top 50 of a chute 111, extending through the floor B and delivering to a suitable receptacle 112 on the floor A. The fan of the assemblage 55 is driven by a belt 113, which connects pulleys 114 on the cam shaft 94, and 115 on the fan shaft.

Particles of tobacco small enough to pass through the meshes of the screen 100, and those larger than the meshes of screen 101 are delivered by a spout 116 extending downwardly and laterally from the box frame to

an endless conveyor to be described. Those particles passing through the screen 101 are delivered through a conduit 117, into a dust receptacle 118 on the floor A.

The fan assemblage 106 has the usual 70 damper mechanism 119, and the casing 77 has an outlet port 120. A hood 121 is arranged above the port, and is connected by a conduit 122 branching from a conduit 123 to an air pump or compressor 124. By means 75 of this pump or compressor the dust is removed from the casing 77, and is delivered to the dust collector 67, by means of a conduit 125.

The outlet 107 of the fan assemblage 106 80 has in connection therewith a separator box 108. The outlet arches through the separator box as shown. The arrangement is such that the leaf portions pass into and out of the separator box, in their travel 85 through the outlet 107. The upper wall of the arch is formed by a perforate plate 128, and the separator box communicates at its top with the air compressor 124 through the conduit 123 before mentioned. The separator box has a door 129 for permitting access thereto, and the discharge outlet 107 delivers onto a conveyor, which returns the leaf portions into the cycle, delivering them to the next to the last disintegrator of the 90 first series.

The said conveyor includes an endless belt or apron 131 supported at its ends by rollers 132. One of these rollers is adjustable as indicated at 133 in Fig. 8, and the other is connected by a belt 134 with the prime mover. The outlet 107 delivers through an extension 135, into a box casing 136, enclosing the upper run of the conveyor, and at its forward end, the upper run delivers into a 105 hopper 137, having a chute 138 discharging into the hopper of disintegrator F.

It will be noticed referring to Fig. 8 particularly, that the forward portion of the belt 131 is substantially horizontal, while 110 the rear portion is inclined. Rollers 141 are provided for changing the direction of the travel of the belt.

The particles of tobacco delivered by the spout 116, fall into the buckets 148 of an 115 endless belt 145. This belt is supported by rollers 146—147. The former is supported below the discharge end of the spout 116, and the latter is supported by the frame work of a fiber fan to be described. The 120 conveyor 145—148 is driven from the prime mover by a belt 149, and the conveyor is so arranged, that the particles of tobacco received from the spout 116, are delivered to the fiber fan.

The fan shown more particularly in Fig. 10 comprises a suitable supporting frame 151, in which is mounted a vibrating screen 152. The screen is arranged transversely of a box frame 153, supported to extend 130

longitudinally of the frame, and to incline downwardly toward the front. Resilient links 154 support the frame, each pivoted at one end to the box frame, and secured to the other to the frame 151. The conveyor 145-148 delivers to a feed table 155, which in turn delivers to the screen near the upper end thereof.

The screen is vibrated by means of a cam 156 on a cam shaft 157 journaled at the rear end of the frame, and connected to the box frame by a link 159, and a follower 158. The tobacco particles, which are too large to pass through the meshes of the screen, are fed down over the lower end thereof, and into the blast from a suitable fan 162 arranged in the fan casing 163 below the box frame. The tangential outlet 164 of the fan casing opens into a chute 165, leading from the front end of the frame 151 to a collector casing 166.

The chute has a gravity discharge 167, discharging through a chute 168 into a suitable receptacle 169 on the floor A. The fan casing has the usual damper 170, and a port is provided in the upper wall of the conduit 165 covered by a perforate screen 171. The port is the inlet end of a conduit 172, communicating with the conduit 123 before mentioned. The tobacco particles which pass through the screen 152, are discharged by a spout 174 at the forward or lower end of the screen, into a receptacle 173 arranged at the side of the fan. The shaft 157 is driven by a belt 160 from the prime mover, and the said shaft is connected to the fan shaft by a belt 161.

The sand screen and riddling device to which the chutes 71 and 72 deliver, Figs. 6 and 7, includes a suitable supporting frame 175, in which is mounted to vibrate and reciprocate an open box frame 176. Three perforate screens 177, 178, and 179 are arranged transversely of the frame which inclines downwardly toward its rear end. The frame is supported by resilient links 180 pivoted to the frame, and rigidly secured to the supporting frame. A cam 181 on a cam shaft 182 vibrates the box frame through a link 184 and a follower 183. The shaft is rotated by means of a belt 185 connecting with the prime mover.

The screen 177 extends the full length of the box frame, while the screens 178 and 179 stop short of the rear end, so that discharge space is provided at this point. A trough 186 is arranged at the rear end of the box frame, to which the screens 178 and 179 deliver. The screen 177 delivers over the rear end of the box frame, onto a conveyor, in the form of a belt 187, supported by rollers 188 and 189.

The roller 188 is arranged below the rear end of the sand screen, while the roller 189 is arranged above the common picking belt

57 before mentioned, delivering to the belt just beyond the disintegrator E. The conveyor is driven by a belt 190 from the prime mover. The particles of tobacco which are too large to pass through screens 177, 178 and 179, are all delivered to the conveyor 187, and to the picking belt. The trough 186 before mentioned also delivers to the conveyor, and only those particles small enough to pass through all the screens are discharged. Such particles are stem particles, and are delivered by a trough 191 into a suitable receptacle 192. The conveyor 187 has a channel shaped member 193 for its upper run, and the conveyors 54 before mentioned are similarly provided.

In operation, the tobacco to be stemmed is arranged on each side of the blending belt, preferably as it comes from the hog-head. An attendant mixes hands from the several heaps in a selected proportion on the blending belt, which delivers it to the dividing mechanism. Another attendant at the point X places the hands as they come on the feed belts 9, with the tips of the hands in approximate alinement. By the cutting mechanism the hands are divided into butt and tip portions, and the tip portions are delivered through the chute 11 onto an endless carrier 195, which moves transversely to the belt 57, and to which the said belt 57 also delivers. Thus the tip portions which have not been subjected to the action of the disintegrator, are mixed with the larger particles of lamina from the disintegrators. The endless belt 195 is supported by rollers 196, and driven by a belt 197 from the prime mover. The disintegrators or thrashers act to break up the leaves, and to separate the lamina from the heavier stem portions. All of the particles of tobacco capable of being lifted by the air blast of a disintegrator are removed therefrom, and delivered onto the belt 57. Those too heavy to be lifted by the blast are passed onto the succeeding disintegrator. A part of those discharged from the last disintegrator are returned into the circulation, at a point where the quantity returned is not greater than that which has been removed. The leaf particles are held in the cycle until all of the lamina is removed from the stem portions, so that the stem portions may be discharged through the appropriate outlets.

It will be evident that by arranging the disintegrators in cascade, the leaf lamina is subjected to a minimum of mutilation. Only those portions which separate from the stem with difficulty are subjected to the action of more than one disintegrator. The portions which are easily separated are delivered from the first, and only the most stubborn pass through all of the disintegrators.

There is a continuous separation of lam-

ina and stem throughout the cycle, and any leaf particles which may reach the dust collectors are returned to the cycle by way of the sand screen and riddle. Those particles which reach the collector 166 discharge onto the picking belt 57 through a chute 199.

I claim:

1. A step in the method of stemming tobacco which consists in the separation and removal prior to the stemming operation of those portions of the tips of the leaves containing the stems of a size utilizable in the further processing of the leaf.

15 2. A step in the method of stemming tobacco, which consists in cutting the leaves transversely in two portions, one of which contains all of the central stem to be removed.

20 3. The method of stemming tobacco, which consists in removing the tip portions of the leaves, subjecting the remaining portion of the leaves to a disintegrating or thrashing operation to separate the leaf portions from the stem portions, and winnowing and screening the leaf portions from the stem portions.

25 4. The method of stemming tobacco, which consists in dividing the leaves transversely into two portions, one of which contains all of the central stem to be removed, subjecting the last named portions to the action of disintegrators or thrashers to separate the leaf portions from the stem portions, winnowing and screening the leaf portions from the stem portions, and adding the leaf portions to the cut off tips.

30 5. The method of stemming tobacco, which comprises removing the tip portions of the leaves with all of the central stem to be retained with the laminæ, subjecting the remaining portions of the leaves to a succession of disintegrating operations to separate the lighter leaf from the heavier stem particles, winnowing out the lighter particles between successive operations and discharging heavier particles by gravity at regular intervals after a selected number of operations.

35 6. The method of stemming tobacco, which comprises removing the tip portions of the leaves with all of the central stem to be retained with the laminæ, subjecting the remaining portions of the leaves to a succession of disintegrating operations to separate the lighter leaf from the heavier stem particles, winnowing out the lighter particles between successive operations and discharging heavier particles by gravity after the succession of operations, and subjecting the remaining portions of the leaves to a succession of alternating disintegrating and screening operations.

40 7. The method of stemming tobacco, which comprises removing the tip portions of the leaves with all of the central stem to

be retained with the laminæ, subjecting the remaining portions of the leaves to a succession of disintegrating operations to separate the lighter leaf from the heavier stem particles while retaining all of the leaves in the succession except the lighter particles, screening the tobacco after it has passed the disintegrators, and returning the remainder of the leaves to the succession.

45 8. Tobacco stemming apparatus, comprising a plurality of disintegrators for breaking the laminæ from the stems, means to divide the leaves into two portions, one containing all of the central stem to be removed, means for conveying the last named portions to the first of the disintegrators, means for feeding the leaves from each disintegrator to the succeeding disintegrator, means in combination with each disintegrator for removing the lighter particles, a common means for receiving such lighter particles, and means for conducting the divided leaf tips to the common receiving means.

50 9. Tobacco stemming apparatus, comprising a plurality of disintegrators for breaking the laminæ from the stems, means to divide the leaves into two portions, one containing all of the central stem to be removed, means for conveying the last named portions to the first of the disintegrators, means for feeding the leaves from each disintegrator to the succeeding disintegrator, means in combination with each disintegrator for removing the lighter particles, a common means for receiving such lighter particles, a gravity discharge for the stem particles, means to deliver the remaining portions of the leaves from the last disintegrator to a preceding disintegrator, and means for conducting the leaf tips to the common receiving means.

55 10. Tobacco stemming apparatus, including a plurality of mechanisms for disintegrating the leaf into lamina and heavier stem portions and for removing the stem portions, a common means receiving the lamina from all of the disintegrating mechanisms, and mechanism to divide the leaves transversely into portions, one containing all of the central stem to be removed, the other containing all of the central stem to be used and for delivering said portions to the first disintegrating means, and to the common receiving means respectively.

60 11. Tobacco stemming apparatus, including a plurality of mechanisms for disintegrating the leaf into lamina and heavier stem portions and for removing the stem portions, a common means receiving the lamina from all of the disintegrating mechanisms, and mechanism to divide the leaves transversely into portions, one containing all of the central stem to be removed, the other containing all of the central stem to

be used and for delivering said portions to the first disintegrating means, and to the common receiving means respectively, each disintegrating mechanism having screening means including an air blast.

12. In tobacco stemming apparatus, mechanism constructed to break up tobacco leaves including the stems, and to separate the lamina from the stem particles, means to constrain the leaves to pass in cycle through said mechanism, means interposed in the cycle for separately removing leaf lamina

substantially free from stem particles and stem particles substantially free from leaf lamina, means to receive the leaf lamina, ¹⁵ and mechanism for transversely dividing the leaves into stem and butt portions, and having means for delivering the butt portions to the disintegrating mechanism, and the tip portions to the receiving means. ²⁰

Signed at Richmond in the county of Henrico and State of Virginia this eighth day of June A. D. 1925.

CHARLES LEWIS ROBERTS.
